C. H. VOLL

AUTOMOBILE TRAFFIC SIGNAL

Filed Sept. 5, 1922

Inventor
Charles H. Voll

By *H. L. C. Reynolds*
Attorney

UNITED STATES PATENT OFFICE.

CHARLES H. VOLL, OF SEATTLE, WASHINGTON.

AUTOMOBILE TRAFFIC SIGNAL.

Application filed September 5, 1922. Serial No. 536,259.

To all whom it may concern:

Be it known that I, CHARLES H. VOLL, a citizen of the United States of America, and resident of the city of Seattle, in the county 5 of King and State of Washington, have invented certain new and useful Improvements in Automobile Traffic Signals, of which the following is a specification.

My invention relates to that type of automobile traffic signals which employ a box or compartment containing electric lights and in which the shape of the box combines with the manner of operating the electric lights so as to make it possible to exhibit a 15 plurality of signals.

The object of my invention is to provide means of this type which will make it possible to exhibit a considerable number of variations in signal indications so as to indicate an intention to turn, either to the right or to the left, to stop, to back up, and if this be desired, other indications.

The particular features of my invention which I believe to be new will be specifically 25 pointed out in the claims.

The accompanying drawings show my invention in the type of construction which I have at present adopted.

Figure 1 is an elevation of the device, one 30 half being in section so as to show the interior construction together with a diagram showing the electric circuits and the switch for controlling the same.

Figure 2 is a perspective of the casing 35 of my device as mounted upon the fender of a car.

It is contemplated that such a signal as herein illustrated and described may be mounted either upon the fender of a car, 40 upon the top, or one upon the front of the car and one at the rear. In fact the position in which the signal is mounted is not any essential part of my invention. It may be mounted wherever it is desired.

I provide a casing 1 of suitable shape to 45 contain the parts necessary to divide the interior thereof into as many compartments and of such size as may be necessary to properly show the various signals desired, 50 and also of such depth as to satisfactorily

receive the lamps which are employed for illuminating the same. This casing should, in the main, be of an opaque material, as metal. It may conveniently be made of thin stamped metal. The left hand half of the 55 casing as shown in Figure 1, is supposed to be a section taken just within the face plate. This is shown as having a series of compartments which divide the interior thereof into a number of chambers, which chambers 60 are illuminated by lamps. These partitions are so constructed that the illumination of one chamber will not effect the illumination of another chamber adjacent thereto. These chambers comprise a central chamber 2 65 which is of rectangular outline and is designed to form the stem of two arrows which point respectively in opposite directions. Adjacent these and at each side is a chamber 20 which forms the major part 70 of the arrow head. Outside of these, at each side, is a chamber 21. This is formed by partitions 22 which are placed at substantially right angles to each other with the point at which they join towards the center. These partitions outline the reentrant angle at the rear end of the arrows which are employed as the signal indications. 75

Between the partitions 22 and the side partitions 23 which form the chamber 20, are 80 chambers 24. In addition to these, chambers 25 are provided at each side of the center and also at each side of the chamber 2 which forms the shaft of the arrows. These are designed for illuminating the beveled triangular section of the arrow which forms the beveled shoulder of the widened rear end. This is clearly indicated at the point 26 at the right hand side of Figure 1. Within each of these chambers is provided a small electric 90 lamp, these being connected up in suitable circuits with the battery 3 and the switch 8 so as to selectively illuminate such lamps as are necessary for bringing out the arrow or other indicating shape which may be employed. The central chamber 2 is illuminated by the lamp 30. On the same circuit therewith are the lamps 31 and 32 which occupy the two chambers 20 at opposite sides of the center. Upon another circuit 100

is placed the lamps 33, 34, 35 and 36. These are designed for illuminating the rear end of the arrow which points towards the right hand. A corresponding circuit contains the lamps 4, 40, 41 and 42 which are designed for illuminating the corresponding portion of the arrow which faces in the opposite direction or towards the left.

In addition, lamps as 43 and 44 are placed in the end of the compartments 21 and are each placed upon a separate circuit and are illuminated conjointly with the respective circuits just described, to which they pertain. The lamp 44 is employed to illuminate the small diamond shaped opening 45 which forms the tip of the arrows. The lamp 43 would be illuminated to illuminate the diamond shaped opening 45 which forms the tip of the arrow pointing to the right, and the lamp 44 to illuminate the corresponding opening of the arrow pointing to the left.

While the chamber 21 is of considerable size, the face plate of the casing which is of opaque character, would have an opening therein showing only the diamond shaped portion indicated at 45 at the right hand side of Figure 1. This same plate also would have its opening of such shape as to outline the composite of the two arrows which are to be illuminated. This would form a triangular opening communicating with each of the chambers 26 which are illuminated by the lamps 33, 36, 4 and 42, respectively. The outline of the opening in the opaque face plate is clearly indicated at the right hand side in Figure 1 and the outline of the partitions which are back of this is clearly shown at the left hand end of Figure 1.

In connection with the signal indications above given other indications may be provided. As illustrated I have shown two arrows, one placed above the arrows just described and pointing upward, and the other placed beneath the same and pointing downward. The opaque face plates of the casing will be provided with openings outlining these arrows, as has been indicated at the right hand side of Figure 1, and which are lettered respectively, 5 and 50. The partitions within the casing may be varied as desired so that they do not encroach upon the shape of the arrow. The shape of the arrow is determined by the opening cut in the face plates.

In addition to the above I have also provided a stop signal which consists of the letters forming the word "Stop". This necessitates the use of two other chambers, 6 and 60, placed at opposite sides of the center line. This may have the outlines of the letters cut therein or it may have the entire face illuminated so as to be seen from the outside and have the letters outlined

therein in an opaque material. Which of these two plans is followed is optional. The chamber 5 is illuminated by a lamp 51 while the chamber 50 is illuminated by a lamp 52. Each of these is placed on its respective circuit controlled by the switch 4. The chambers 6 and 60 which contain the lamps 61 and 62, both of which are on the same circuit, are each provided with one lamp.

The type of switch which I have shown consists of a lever 8 pivoted at one end and containing a contact member upon its face adapted when it is shifted to make connections with a series of bars by which the various circuits are controlled. These bars are arranged in arcuate position, which are successively at different distances from the pivot center of the arm 8. The bars 7 which form the outer series are three in number. This is also true of the next inner series 70. The series 71 which are necessary inside of this are four in number, while the series 72, being the innermost series, are also four in number. The switch lever 8 is connected with the battery 3 by a common lead 80, and the battery is connected with the lamps through a series of leads, shown connected with the terminal 81 of the battery, each leading to its respective sets of lamps and the lamps are connected with the terminals of the switch by other leads 82, 83, 84, 85 and 86. The lamps connected with the various circuits are controlled in their illumination by the movement of the switch lever or arm 8. This has four positions of illumination. The type of signal indication which it is desired to display is controlled by the position of the lever arm 8.

The casing 1 may be single faced, that is having only one face illuminated, or it may be double faced, having both faces illuminated, as may be desired. Such a casing, mounted where it may be easily seen both from the front and the rear may be sufficient for a car. If desired, however, the casing may be duplicated and placed one at the front and one at the rear, in which case the illumination of a single face would be sufficient. It is evident that the shape of the signal indication may be varied as desired, and also that the illumination of lights which would form a readable signal may be employed in substitution for the arrows or other shape of the indicating signal.

What I claim as my invention is:

A traffic signal for automobiles comprising a signal box having partitions extending from the face thereof inwardly and dividing it into a central horizontal chamber outlining the shaft of a conventional arrow, right and left chambers one at each end of said central chamber outlining a conventional arrow head having its tip cut off by a

re-entrant point which forms the re-entrant of the angle at the wing end of a conventional arrow, two chambers at opposite sides of each arrow head complementally with 5 said arrow head outlining the wings of a conventional arrow, and a chamber at each end having a window outlining the tip of each arrow head, illuminating means in said chambers and means for selectively con-

trolling said illuminating means to illuminate only the central chamber and the right and left chambers or to illuminate the chambers which form an arrow pointing in either direction.

Signed at Seattle, King County, Washington, this 24th day of August, 1922.

CHARLES H. VOLL.
